UNITED STATES PATENT OFFICE.

MELVIN T. STONE, OF SAN ANTONIO, TEXAS.

HYDROCARBON-BURNER.

1,111,929.

Specification of Letters Patent. Patented Sept. 29, 1914.

Application filed November 12, 1913. Serial No. 800,547.

To all whom it may concern:

Be it known that I, MELVIN T. STONE, a citizen of the United States, residing at San Antonio, in the county of Bexar and State of Texas, have invented new and useful Improvements in Hydrocarbon-Burners, of which the following is a specification.

The invention relates to burners, and more particularly to the class of hydrocarbon burners.

The primary object of the invention is the provision of a burner wherein kerosene can be used as a fuel which is generated into gas for heating purposes, the burner being of novel construction so as to enable the proper feed of the fuel therethrough and also to obviate the formation of carbon, which results in the clogging of the burner.

Another object of the invention is the provision of a burner wherein the gas will be generated quicker and more perfectly, and also which can be easily cleaned so as to avoid the clogging of the burner.

A further object of the invention is the provision of a burner wherein the fuel is caused to spread throughout the largest possible surface, thereby allowing it to be more rapidly converted into gas than would be the case if the oil were fed in a column thereto.

A still further object of the invention is the provision of a burner wherein the oil and gas are caused to travel a maximum distance through a flame before it strikes the outlet therefor, thus superheating and assuring perfect generation or the converting of the fuel into gas and producing a more intense heat.

A still further object of the invention is the provision of a burner which is extremely simple in construction, thoroughly reliable and efficient in its operation, and inexpensive in manufacture.

With these and other objects in view, the invention consists in the construction, combination and arrangement of parts as will be hereinafter fully described, illustrated in the accompanying drawings, and pointed out in the claims hereunto appended.

In the drawings:—Figure 1 is a side elevation of a burner constructed in accordance with the invention. Fig. 2 is a top plan view thereof. Fig. 3 is a vertical longitudinal sectional view through the same.

Similar reference characters indicate cor-

responding parts throughout the several views in the drawings.

Referring to the drawings in detail, the burner comprises a vaporizing coil 10 connected at one end through the medium of a union 11 to a liquid induction pipe 12, while its opposite end has connected thereto a union 13 engaged with a branch 14 forming a gas chamber, which is vertically disposed, while the coil 10 is at right angles thereto. Connected to the branch 14 is an elbow coupling 15 in which is engaged a horizontal branch 16 closed at its outer end through the medium of a cap 17, the branch 16 being provided with a flame port 18. The induction pipe 12 is disposed parallel with the branch pipe 16, the latter being arranged beneath the coil 10 so that when a flame issues from the port 18 it will play upon the coil for heating the liquid fuel therein to vaporize the same for the production of gas. The induction pipe 12 has fitted thereon a spreader head 19 against which plays the flame from the flame port 18 for the spreading of the said flame throughout the area of the coil 10 during the use of the burner.

Threaded in the induction pipe 12, and communicating therewith, is an injector nipple 20 to which is connected a liquid feed pipe 21, the same being connected with a suitable pressure air tank for delivering oil into the induction pipe 12 whereby it may be vaporized into gas.

Arranged within the coil 10, and extended through the induction pipe 12, branch 14, and branch pipe 16, is a coiled wire 22, through the center of which extends a single wire forming a core 23, these wires being designed to distribute the oil which is under pressure, the center wire 23 being designed as a lead wire for the oil, while the coiled wire 22 serves to spread the oil out thinly within the burner structure so as to have the same travel over a maximum surface, thereby allowing it to be more rapidly converted into gas when heated by the flame at the branch pipe 16 of the said burner. Furthermore, the arrangement of the wires 22 and 23 in the burner minimizes the possibility of the formation of carbon therein so as to avoid the choking of the burner thereby. Also on separating the coil from the induction pipe 12 or detaching the branch 14 and the branch pipe 16 the coiled wire 22

will clean the pipes to remove any carbon which might have formed therein.

From the foregoing it is thought that the construction and manner of operation of the device will be clearly understood, and therefore a more extended explanation has been omitted.

What is claimed is:

1. A hydrocarbon burner comprising an induction pipe, a branch having communication therewith, a further pipe having a combustion opening connected with the branch and arranged below the induction pipe, a coiled wire trained through the induction pipe, branch, and last-named pipe for spreading the fuel throughout the maximum area thereof, a single wire passed through the coiled wire throughout the extent of the induction pipe, branch, and last-named pipe for spreading the fuel throughout the maximum area thereof, and a single wire passed through the coiled wire throughout the extent of the induction pipe, branch, and last-named pipe.

2. A hydrocarbon burner comprising an induction pipe, a branch having communication therewith, a further pipe having a combustion opening connected with the branch and arranged below the induction pipe, a coiled wire trained through the induction pipe, branch, and last-named pipe for spreading the fuel throughout the maximum area thereof, a single wire passed through the coiled wire throughout the extent of the induction pipe, branch, and last-named pipe, and a spreader arranged in the path of the flame when issuing from the combustion opening.

In testimony whereof I affix my signature in presence of two witnesses.

MELVIN T. STONE.
